CLAIM

The ornamental design for a transnasal conduit, as shown and described.

DESCRIPTION

FIG. 1 is a side perspective view of a transnasal conduit, showing my new design, the broken lines of the straps being shown for illustrative purposes only and forming no part of the claimed design;

FIG. 2 is a bottom plan view thereof;

FIG. 3 is a top plan view thereof;

FIG. 4 is a left side view thereof;

FIG. 5 is a right side view thereof;

FIG. 6 is a rear view thereof; and,

FIG. 7 is a front view thereof.
